UNITED STATES PATENT OFFICE.

SIGURD THRONSEN, OF CHICAGO, ILLINOIS, ASSIGNOR TO WESTERN ELECTRIC COMPANY, INCORPORATED, OF NEW YORK, N. Y., A CORPORATION OF NEW YORK.

METHOD OF AND MECHANISM FOR WINDING STRAND MATERIAL.

Application filed December 29, 1923. Serial No. 683,302.

This invention relates to a method of and a mechanism for winding strand material, and more particularly to a method for spooling tinsel ribbon.

It is desirable in the spooling of tinsel ribbon that the lay and distribution of the ribbon be such that each layer of the ribbon will unwind freely and without the slightest catch on the adjacent helices, or lower layers wound, or on the flanges of the spool. In order to attain such spooling it is essential that the distribution of the ribbon be uniform across the face of the spool, and that neither ridges nor openings be formed adjacent to the flanges of the spool, otherwise the ribbon may be forced underneath the lower layers or wedged adjacent to the flanges of the spool.

An object of this invention is to provide an improved method for spooling ribbon at high speeds and in such manner that the ribbon may be readily unwound from the spool and will not tangle or be subjected to stresses or strains which might deform or break it.

Another object of this invention is to provide a simple and inexpensive mechanism by which the above described method may be performed.

A mechanism made in accordance with the invention comprises, briefly, a rotatable spindle, a spool capable of being mounted on said spindle, a distributor finger, a cam for guiding and moving forward said finger, and resilient means for moving said finger, guided by the said cam, back to its starting position.

Other objects and advantages of the invention will more fully appear from the following detailed description taken in connection with the accompanying drawings which illustrate an apparatus by which the method may be performed.

In the drawings,

Fig. 1 is a fragmentary plan view of a tinsel ribbon spooling mechanism and driving means thereof;

Fig. 2 is a fragmentary front view of the tinsel ribbon spooling mechanism partly in section;

Fig. 3 is a right-hand end view of Fig. 1, and

Fig. 4 is a section, on an enlarged scale, taken through the center of the spool showing the lay of the ribbon thereon.

The improved method for spooling tinsel ribbon will be readily understood by a description of an apparatus by which it may be performed.

Referring now to the drawings in detail in which like reference numerals designate similar parts throughout the several views, 10 indicates a steel spool which is suitably mounted on a rotatable spindle 11 and held thereon tightly against a flange 12, which is secured to the spindle 11 by a knurled clamping nut 13. Mounted loosely around the spindle 11 is a spiral gear 14 having a prolonged hub 15, on the end of which is formed a cam 16, the said gear 14 rotating the cam 16 relatively to the spool 10. The gear 14 is actuated by a pinion gear 17 secured to a rotatable shaft 18, which is in turn driven by a spiral gear 19 attached thereto, the said gear meshing with a small gear 20 suitably attached to the spindle 11. Secured to the spindle 11 is a friction drive pulley 21 which is driven by another friction drive pulley 22, said pulley being actuated by a small pinion gear 23, which meshes with a spiral gear 24 secured to a power driven shaft 25.

Suitably located immediately beneath the spool 10 is a distributing finger 30, which is secured to a key member 31 capable of being reciprocated in a key-way 32 formed in a stand 33. Secured to the key member 31 is a small stud 34 which projects into a slot 35 in the stand 33. Between the stud 34 and an end piece 36, which is secured to the end of the stand 33, is a compression spring 37. Covering the top of the key-way 32 and the sides of the stand 33 is a plate 38 which is suitably fastened thereon.

The operation of the mechanism is as follows:

The spool 10 is mounted in place on the spindle 11 and the tinsel ribbon 40 is drawn from a supply source (not shown), threaded through the distributor finger 30 and then wrapped around the spool 10.

Upon connecting the source of power, which may be a motor (not shown), suitably connected to the shaft 25, the spindle 11 is caused to rotate, revolving the spool 10, which is secured thereto, and also causing the cam 16 to rotate through the gear train previously described. The cam 16 upon being actuated moves the finger 30 forward, distributing the ribbon 40 across the face

of the spool 10, and causes the spring 37 to become compressed. Upon reaching the end of the forward throw of the cam 16, the finger 30 is forced back, guided by the cam 16, to its normal position by the spring 37.

The throw of the cam must be such as to enable the ends next to the flanges of the spool to fill evenly with the center of the spool. If the cam throw is made too great, 10 the ribbon piles at the ends of the spool, whereas too short a cam throw causes the formation of openings which permits upper layers to slide underneath the lower ones, or to wedge next to the flanges of the spool.

15 By changing the ratio of the driving gear train, the cam 16 may be made to rotate faster or slower than the spool 10. The ratio of the speed of the cam 16 to the speed of the spool 10 determines the pitch of the 20 ribbon lay and the amount of lag in the ribbon, the lag being directly proportioned to the pitch of the lay.

A ratio that has obtained good results 25 is one revolution of the cam to 494-10/29 revolutions of the spool, or a pitch of the lay of approximately .005". If the ribbon is about .012" this lay causes an overlapping 30 of the ribbon of about .007". The ratio being uneven shifts the starting point of spooling to a different place at every turn of the cam.

35 By maintaining a very small pitch and lag the ribbon is wound on the spool in overlapping helices (Fig. 4), the individual turns 46 of each helix overlapping at 47. Furthermore in reducing the angle of the lag to a minimum it is possible to guide the 40 ribbon for distribution practically clear up to the flanges of the spool, as indicated at 48 (Fig. 4).

The advantage of winding ribbon in accordance with the present invention is readily apparent in that, due to each turn of

the ribbon overlapping the adjacent turn, the ribbon coils in being unwound are necessarily prevented from catching upon or engaging the edges of each other. Furthermore, tinsel ribbon so wound may be withdrawn at practically right angles to the face of the spool, thus decreasing the possibilities of tangling, as well as to greatly reduce the tension and stress on the ribbon. Then too, in winding ribbon in accordance with the method disclosed the ribbon may be guided for distribution practically clear up to the flanges of the spool, reducing the number of ridges and openings adjacent to the flanges of the spool and permitting a much more uniform distribution, which results in freedom from tangling in unwinding the ribbon. 60

What is claimed is:

1. In a mechanism for storing tinsel ribbon in such manner that it may be withdrawn from storage without tangling, an arbor for receiving a take-up spool, means for rotating said arbor, a distributor, and means rotated about the axis of said arbor at a speed to cause the movement of said distributor so that the tinsel ribbon is wound on the spool in helices having approximately a 50% overlap. 65

2. In a mechanism for storing tinsel ribbon in such manner that it may be withdrawn from storage without tangling, an arbor for receiving a take-up spool, means for rotating said arbor, a distributor, and means rotated about the axis of said arbor at a considerably slower speed than said arbor to cause the movement of said distributor so that the tinsel ribbon is wound 70 on the spool in helices having approximately a 50% overlap. 80

In witness whereof, I hereunto subscribe my name this 20th day of December, A. D. 1923.

SIGURD THRONSEN.
